UNITED STATES PATENT OFFICE.

EDWARD STUTZER, OF BROOKLYN, NEW YORK, ASSIGNOR TO VICTOR NAILING MACHINE COMPANY INC., OF BROOKLYN, NEW YORK, A CORPORATION OF NEW YORK.

NAILING-MACHINE.

1,356,894.

Specification of Letters Patent. Patented Oct. 26, 1920.

Application filed November 11, 1919. Serial No. 337,148.

To all whom it may concern:

Be it known that I, EDWARD STUTZER, a citizen of the United States, and residing at Brooklyn, in the county of Kings and State 5 of New York, have invented certain new and useful Improvements in Nailing-Machines, of which the following is a specification, such as will enable those skilled in the art to which it appertains to make and use 10 the same.

This invention relates to machines for driving nails and particularly to machines of this class designed for use in nailing down floors and particularly what are 15 known as parquet floors; and the object of the invention is to provide a portable machine of the class and for the purpose specified which is so constructed as to permit of its free movement about from place to place 20 by hand as well as to facilitate the driving of nails in inconvenient places, such as corners, grooves and the like; and with this 25 and other objects in view the invention consists in a machine of the class and for the purpose specified which is simple in construction and operation and efficient in use.

This invention is an improvement on that described and claimed in U. S. Letters Patent No. 1,060,377 granted to me April 29, 30 1913, and is fully disclosed in the following specification, of which the accompanying drawing forms a part, in which the separate parts of my improvement are designated by suitable reference characters in 35 each of the views, and in which;—

Figure 1 is a front view of my improved machine with part of the construction broken away and in section; and indicating the method of its use;

40 Fig. 2 a partial section on the line 2—2 of Fig. 1;

Fig. 3 a partial section on the line 3—3 of Fig. 2;

Fig. 4 a view similar to Fig. 1 but showing 45 only a detail of the construction and on an enlarged scale and with part of the construction broken away and in section;

Fig. 5 a partial section on the line 5—5 of Fig. 4;

50 Fig. 6 a view similar to Fig. 2 but show-

ing only a part of the construction on an enlarged scale and with parts in a different position;

Fig. 7 a partial section on the line 7—7 of Fig. 4;

55

Fig. 8 a partial section on the line 8—8 of Fig. 6; and,

Fig. 9 a partial section on the line 9—9 of Fig. 1.

In the practice of my invention I provide 60 a main frame 10 which is elongated in form and composed of two parallel channel bars 11, the channels of which are directed inwardly toward each other, and these bars are joined at the top by a cross piece 12 65 having a forwardly directed extension 13, and to one side of the cross piece is secured a handle member 14. A supplemental frame 15 is secured to and between the side bars 11 adjacent to the lower end portion thereof 70 and at a predetermined distance from the lower ends of said bars.

A nail support and guiding member 16 is movably mounted in the supplemental frame 15 and comprises a top cylindrical 75 portion 17 and a reduced bottom portion 18, which passes through the bottom of the supplemental frame 15, while the top cylindrical portion 17 normally projects beyond the top of the supplemental frame 15 80 as shown at 19 and a spiral spring 20 is mounted in the supplemental frame 15 and operates to normally hold the member 16 in a raised position. The member 16 is provided with a central bore 21 which opens 85

outwardly through the top and bottom ends of said member, the top portion of said bore being enlarged as shown at 22. A nail driving rod 23 is mounted to move vertically in the bores 21 and 22, and is normally held 90 in a raised position by a spring 24, as clearly shown in Fig. 6 to normally project the upper end portion 25 of the rod 23 beyond the top of the member 16, as shown in said figure.

95 The top of the member 16 is provided with a plate 26 having a fibrous facing 27, both of which are held in position by screws 28, while the bottom face of the member 16, or the extension 18 thereof, is provided with 100

a fibrous facing 29 held in place by screws 30. One side of the member 16 is cut out to form an aperture 31 as clearly shown in Figs. 6 and 8, which is placed in communication with the bore 21 by a passage 32 shown in Fig. 6.

A nail feeding hopper 33 is connected with the top portion of the supplemental frame 15, as clearly shown in Figs. 1 and 6 10 and is placed in communication with the aperture 31 of the member 16 by a port or passage 34. The member 16 is provided approximately centrally thereof with two forwardly directed ears 35 through which 15 is passed a pin 36 on which is rotatably mounted a nail delivery device 37 consisting of top and bottom, similarly formed, disks 38 provided in the periphery thereof with a plurality of notches 39 in vertical 20 alinement. The disks 38 are spaced apart by a ratchet wheel 40 to which said disks are secured and as will be seen the disks 38 project into and are adapted to operate in the aperture 31 of the member 16 to control 25 the passage of nails through the aperture 31 into the bottom portion of the bore 21 of the member 16.

A main lever 41 is pivoted to a cross piece 42 secured to the bars 11 approximately centrally thereof, as clearly shown in Figs. 2 30 and 3. The lower end portion of the lever 41 operates in a guide member 43, connected with and forming part of the supplemental frame 15 and the main frame 10, said lever 35 being cut out as shown at 44 where it operates in said guide member.

The lower end of the lever 41 is bent outwardly, downwardly and inwardly to form a support 45 for a pawl 46 which operates 40 in connection with the ratchet wheel 49, the pawl 46 being normally held in engagement with the ratchet wheel by a spring 47. A spring finger 48 is secured to the supplemental frame 15 and operates in connection 45 with the ratchet 40 to hold it against rotation in one direction, all this construction being clearly shown in Figs. 1 and 8 of the drawing.

The upper end portion of the main lever 50 41 is cut out as shown at 49 and provided above the cut-out portion 49 with an enlarged cam portion 50, and the upper end of said lever passes through and operates in an elongated aperture 51 in the extension 13 of 55 the cross piece 12 as clearly shown in Figs. 1 and 2.

The main frame 10 is provided approximately centrally thereof with a cross member 52 which extends forwardly and aids in 60 supporting a nail receiving casing or hopper 53, and it will be noted that the lever 41 passes through and operates in a slot 54 in the cross member 52 of the frame, as clearly shown in Fig. 2. A bar 55 passes through 65 and operates in the cross member 52, said

bar being provided at its lower end with a hammer head 56 adapted to operate in connection with the member 16 as clearly shown in Figs. 1 and 2. The hammer head is provided on the opposite sides thereof 70 with extensions 57 which operate in the channels of the side bars 11 of the main frame which in combination with the cross bar 52 serves to guide the bar 55 and hammer head 56 in their vertical movement. A 75 spiral spring 58 is mounted on the bar 55 between the cross member 52 and the hammer head 56 and serves to normally hold the hammer head and bar in a depressed position.

A supplemental handle member 59 is secured to the bar 55 above the cross member 52 and by means of which the bar 55 and hammer head 56 may be raised and lowered in the main frame 10, the inner 80 end of the handle member 59 being apertured as shown at 60 to receive the lever 41, whereby in the upward movement of said handle member, the lever 41 will be moved laterally on its pivot by reason of 85 the cam-shaped portion 50 on the upper end portion of said lever. In the upward movement of the bar 55, the upper end portion thereof, passes through an aperture 61 in the top of the cross piece 12 of the main 90 frame 10.

The nail receiving casing or hopper 53 is provided approximately centrally thereof with a shaft 62 on which is mounted within said casing a drum 63, the periphery of 100 which is provided with a plurality of pairs of projecting pins 64 which are adapted to automatically pick up the nails 65 in the casing 53 to feed the same, one by one, into the machine. The bottom of the casing 53 is 105 curved as shown at 66 in Fig. 1 to bring the nails 65 into contact with the periphery of the drum 63 to enable the separate pairs of pins to engage said nails and deliver them through an opening or discharge 67 at one 110 side of the bottom of the casing 53 through which the nails drop into a chute 68 at the bottom of the casing 53 and pass downwardly over a slotted guide and supporting member 69, as clearly shown in Figs. 1, 4, 115 5 and 7. The free end portion of this member is provided with an enlarged slot or opening 70 through which the nails 65 are adapted to drop into the hopper 33.

The dropping of the nails into the hopper 120 33 is controlled by a nail feeding device 71 supported on an arm 72, secured to one side of the main frame 10, as shown at 73 in Fig. 5, and this feeding device consists of a top 125 disk 74, the periphery of which is provided with a plurality of notches 75, and below said disk is a supplemental disk 76 having a plurality of spaced and projecting pins 77. Below the supplemental disk 76 is a ratchet wheel 78 in connection with which a pawl 130

79 pivoted to the arm 72 operates to prevent the rotation of said ratchet wheel in one direction.

Pivoted to the lever 41 in line with the 5 feeding device 71 as shown at 80 in Fig. 5 is a spring lever 81, one end of which is provided with a finger 82 adapted to normally engage the teeth of the ratchet wheel 78, and the other end of which is provided with a spring 83, which normally holds the finger 82 in operative connection with said ratchet wheel, as clearly shown in Fig. 5.

The guide and supporting member 69 is 15 provided adjacent to the feeding device 71 with an enlarged portion 84 at one side thereof, in which is mounted a tensionally operated pin 85 having an outwardly directed arm 86 which is adapted to operate 20 in connection with the pins 77 of the feeding device 71 to move the pin 85 against the tension of the spring 87. The pin 85 is adapted to operate in connection with the nails 65, or one of said nails supported in a 25 member 69 to normally hold said nail against movement into the feeding device 71 until the pin 85 is released by a pin 77.

Pivoted to a cross piece 88 secured to the main frame 10 is a supplemental lever 89, 30 the lower end of which is pivoted to the lever 41 as shown at 90 and the upper end of which carries a spring operated pawl 91, which operates in connection with a ratchet wheel 92 on the inner end of the shaft 62 of the drum 63, and by means of the supplemental lever 89 the drum 63 is given an intermittent rotary movement in one direction in the operation of the lever 41, as hereinafter described. The supplemental 35 frame 15 is enlarged at one side thereof as shown at 93 in Figs. 1 and 9 and a sleeve 94 is mounted in this enlargement and projects at one side thereof, and mounted within the sleeve 94 is a spring operated pin 95, 40 the outer end of which is provided with a head 96 which operates in connection with the lever 41, which lever normally holds the pin 95 in its extended position whereby on the inward movement of the lever 41 the spring 97 on the pin 95 will move said pin 45 inwardly into the aperture 34 to engage a nail therein, or prevent the passage of more than a single nail from the aperture 34 or the cut-out portion 31 downwardly into the bore 21.

From the foregoing the operation of my improved portable nail driving machine will be readily understood when taken in connection with the accompanying drawings 50 and the following statement. The normal position of the various parts of the machine is that shown in Figs. 1 and 2, and when it is desired to drive a nail into a floor or other surface, the machine is placed upon the 55 floor or other surface indicated at 98 in

Fig. 6 so that the bottom of the frame 10 rests upon the floor and the member 16, or the extension 18 thereon, also rests upon the floor, after which the handle member 59 is grasped by one hand of the operator and 60 is pulled upwardly, which operation raises the bar 55 and hammer head 56 in the frame 10 against the tension of the spring 58. In this operation, the lever 41 or the lower end portion thereof is moved inwardly by 65 the operation of the cut-out portion 60 of the handle member 59 on the cam portion 50 of said lever, the inward movement of the lower end portion of the lever 41 moves the pawl 46 inwardly to rotate the delivery 70 device 37 so as to bring one of the notches 39 on each of the disks 38 in alignment with the cut-out portion 31 of the member 16 to permit a nail 65 to drop into the position shown in Fig. 6. In this operation the 75 spring operated pin 95 prevents the drop of the other nails through the delivery device on the inward movement of the lever 41, as above described, the lever 81 pivoted to said lever 41 is also moved inwardly to 80 rotate the nail feeding device 71 to bring one of the notches 75 of the disk 74 in line with the enlarged slot or opening 70 of the member 69, as clearly shown in Fig. 5, to permit one of the nails 65 to drop into 85 the hopper 33. In this last named operation, it will be apparent, on a consideration of said figure, that the pin 85 holds the next adjacent nail 65 against movement. In the inward movement of the lever 41 the 90 supplemental lever 89 is also oscillated on its pivot to rotate the drum 63 in the casing 53 by reason of the engagement of the pawl 91 with the sprocket wheel 92 on the shaft 62 of said drum.

After the handle member 59 has been raised to the full extent and the various operations, above described, completed this handle member is moved downwardly by the operator, who exerts sufficient force on 100 the handle member as to drive the nails 65 partially into the floor or floor surface 98 as indicated at 99 in Fig. 6, it being apparent that the hammer 56 in its downward movement strikes the projecting end 110 portion 25 of the hammer rod 23, which rod drives the nail, as above described.

The handle member 59 is again raised in the manner hereinbefore set out and, in this operation, the nail delivery device 37 115 and the nail feeding device 71 will again be operated to bring the unnotched portions of the disks 38 and 74 respectively into line with the cut-out portion 31 and enlarged slot 70 respectively, to prevent the passage of 120 other nails through said delivery and feeding devices. It will be apparent that in the last named operation of the nail feeding device, one of the pins 77 will engage the finger 86 to release the pin 85 from one of the nails 125 130

- 65 held thereby to permit this nail to drop into position to engage an unnotched portion of the disk 74. It will also be apparent that the drum 63 is operated in the last 5 named operation to continue the feeding of the nails 65 onto the member 69 so as to keep a plurality of said nails always in position ready for passage into and through the feeding device.
- 10 The handle member 59 is again moved downwardly, as above set out, and in this operation the plunger rod 23 drives the nail 65 fully home as indicated at 100 in Fig. 6, and at the same time countersinks the head 15 of this nail as is shown at 101 at the left of Fig. 6, where I have shown a nail previously driven into the floor or other surface 98.

From the foregoing, it will be apparent 20 that my improved machine is much the same in general operation as that of the nailing machine shown and described in the patent hereinbefore referred to, except that the various details of construction for accomplishing the desired result are changed to suit 25 the machine as constructed. The chief feature of my present invention is in the provision of a comparatively light machine which can be readily carried around from 30 place to place by the operator and placed in the desired position when a nail is to be driven and to drive said nail without exerting a great amount of effort. It is also apparent that the machine will be made of sufficient height to enable the operator to comfortably manipulate the machine when in a 35 standing posture.

It will also be understood that while I 40 have described the machine as being operated to drive nails by two strokes of the hammer head 56, it will be apparent that I am not necessarily limited to this construction, as the nails may be driven in a single 45 operation, if desired, and various other changes in and modifications of the details of construction herein shown and described may be made, within the scope of the appended claims, without departing from the spirit of my invention or sacrificing its 50 advantages.

Having fully described my invention, what I claim as new and desire to secure by Letters Patent, is:—

1. A nail driving machine comprising a 55 suitable frame, a nail driving element movably mounted in said frame, means for intermittently delivering nails into position to be driven by said element, means movably mounted in the frame and adapted to operate said element in one movement of said 60 means, a handle member on said last named means and by means of which the same is operated, means for intermittently feeding nails to the nail delivering means, means for 65 operating said nail delivering means and

nail feeding means in one movement of said handle member, a nail receiving casing, a drum in said casing, and means operated by said last named means for rotating said drum.

70

2. A nail driving machine of the class described comprising an elongated frame, a nail receiving casing, means rotatably mounted in said casing for picking up and discharging nails therefrom, a nail feeding 75 device, means for conveying the nails discharged from said casing to said feeding device, a nail delivery device, means for conveying the nails from said feeding device to said delivery device, a tensionally operated 80 hammer rod mounted in the frame in juxtaposition to the nail delivery device, means for conveying nails from the delivery device into position to be operated by said hammer rod, and means movable longitudinally of 85 the frame for operating said hammer rod.

3. A nail driving machine of the class described comprising an elongated frame, a nail receiving casing, means rotatably mounted in said casing for picking up and discharging nails therefrom, a nail feeding device, means for conveying the nails discharged from said casing to said feeding device, a nail delivery device, means for conveying the nails from said feeding device to 95 said delivery device, a tensionally operated hammer rod mounted in the frame in juxtaposition to the nail delivery device, means for conveying nails from the delivery device into position to be operated by said hammer rod, and a handle member connected with said last named means and by means of which the same is operated.

100

4. A nail driving machine of the class described comprising an elongated frame, a nail receiving casing, means rotatably mounted in said casing for picking up and discharging nails therefrom, a nail feeding device, means for conveying the nails discharged from said casing to said feeding device, a nail delivery device, means for conveying the nails from said feeding device to said delivery device, a tensionally operated 110 hammer rod mounted in the frame in juxtaposition to the nail delivery device, means for conveying nails from the delivery device into position to be operated by said hammer rod, means movable longitudinally of 115 the frame for operating said hammer rod, a handle member connected with said last named means and by means of which the same is operated, a lever pivotally mounted in the frame and operated in 120 the movement of said last named means, and means connected with said lever for operating said nail feeding device.

5. A nail driving machine of the class described comprising an elongated frame, a 130

- 5 nail receiving casing, means rotatably mounted in said casing for picking up and discharging nails therefrom, a nail feeding device, means for conveying the nails discharged from said casing to said feeding device, a nail delivery device, means for conveying the nails from said feeding device to said delivery device, a tensionally operated hammer rod mounted in the frame in juxtaposition to the nail delivery device, means for conveying nails from the delivery device into position to be operated by said hammer rod, means movable longitudinally of the frame for operating said hammer rod, a handle member connected with said last named means and by means of which the same is operated, a lever pivotally mounted in the frame and operated in the movement of said last named means, means connected with 10 said lever for operating said nail feeding device, and means connected with said lever for operating said nail delivery device.
- 10 6. A nail driving machine of the class described comprising an elongated frame, a nail receiving casing, means rotatably mounted in said casing for picking up and discharging nails therefrom, a nail feeding device, means for conveying the nails discharged from said casing to said feeding device, a nail delivery device, means for conveying the nails from said feeding device to said delivery device, a tensionally operated hammer rod mounted in the frame in juxtaposition to the nail delivery device, means for conveying nails from the delivery device into position to be operated by said hammer rod, means movable longitudinally of the frame for operating said hammer rod, a handle member connected with said last named means and by means of which the same is operated, a lever pivotally mounted in the frame and operated in the movement of said last named means, means connected with 15 said lever for operating said nail feeding device, and means connected with said lever for operating said nail delivery device.
- 15 7. A nail driving machine of the class described comprising an elongated frame, a nail receiving casing, means rotatably mounted in said casing for picking up and discharging nails therefrom, a nail feeding device, means for conveying the nails discharged from said casing to said feeding device, a nail delivery device, means for conveying the nails from said feeding device to said delivery device, a tensionally operated hammer rod mounted in the frame in juxtaposition to the nail delivery device, means for conveying nails from the delivery device into position to be operated by said hammer rod, means movable longitudinally of the frame for operating said hammer rod, a handle member connected with said last named means and by means of which the same is operated, a lever pivotally mounted in the frame and operated in the movement of said last named means, means connected with 20 said lever for operating said nail feeding device, and means connected with said lever for operating said nail delivery device.
- 20 8. In a portable nail driving machine, an elongated frame, a tensionally operated member movably mounted in one end portion of said frame, a tensionally controlled hammer rod mounted in said member, a tensionally controlled hammer member independent of said rod and mounted to move 25 longitudinally of said frame toward and from said hammer rod and said first named member and to operate said rod, an intermittent nail delivery device for delivering nails into position to be driven by said rod, a nail feeding device for intermittently feeding nails to said nail delivery device, and means in the frame operated in the movement of said hammer member for actuating said nail delivery and feeding devices. 30
- 30 9. A nail driving machine comprising a suitable frame, a nail driving element movably mounted in said frame, a rotary nail delivery device for intermittently feeding nails into position to be driven by said element, means movably mounted in the frame and adapted to operate said element in one movement of said means, a rotary nail feeding device for intermittently feeding nails to the nail delivery device, and means for operating said nail delivery and feeding devices in one movement of said first named means. 35
- 35 10. A nail driving machine of the class described comprising a frame, a nail receiving casing, a nail feeding device, means for conveying the nails discharged from said casing to said feeding device, a nail delivery device, means for conveying the nails from said feeding device to said delivery device, a tensionally operated hammer rod mounted in the frame, means for conveying nails from the delivery device into position to be operated by said hammer rod, and means movable longitudinally of the frame for operating said hammer rod. 40
- 40 11. In a portable nail driving machine, a frame, a member movably mounted in one end portion of said frame, a hammer rod mounted in said member, a hammer member independent of said rod and mounted to move longitudinally of said frame toward and from said hammer rod and said first named member and to operate said rod, a nail delivery device for intermittently de 45

livering nails into position to be driven by said rod, a nail feeding device for intermittently feeding nails to said delivery device, and means in the frame operated in the 5 movement of said hammer member for actuating said nail delivery and feeding devices.

In testimony that I claim the foregoing as

my invention I have signed my name in presence of the subscribing witnesses this 10th day of November 1919.

EDWARD STUTZER.
